DESIGN FOR A SEESAW

Edward M. Flesh, Ferguson, and Vincent J. Micotto, St. Louis, Mo.

Application June 19, 1944, Serial No. 114,075

Term of patent 3½ years

(Cl. D34—5)

To all whom it may concern:

Be it known that we, Edward M. Flesh, a citizen of the United States and resident of Ferguson, county of St. Louis, State of Missouri; and Vincent J. Micotto, a citizen of the United States and resident of the city of St. Louis, State of Missouri, have invented a new, original, and ornamental Design for a Seesaw, of which the following is a specification, reference being had to the accompanying drawing, forming a part thereof.

Fig. 1 is a perspective view of a seesaw showing our new design;

Fig. 2 is a top plan view;
Fig. 3 is a side elevational view;
Fig. 4 is a bottom plan view; and
Fig. 5 is an end elevational view thereof.
We claim:
The ornamental design for a seesaw, substantially as shown.

EDWARD M. FLESH,
VINCENT J. MICOTTO.
